United States Patent Office.

ALEXANDER WHITE, OF GENESEO, ILLINOIS.

Design No. 3,653, dated August 31, 1869.

DESIGN FOR STOVES.

The Schedule referred to in these Letters Patent and making part of the same.

To all whom it may concern:

Be it known that I, ALEXANDER WHITE, of the city of Geneseo, and State of Illinois, have originated and designed a new Design for Stoves, of which the following is a full, clear, and exact description, reference being had to the accompanying photograph, making part of this specification.

At the right side of the base of the stove is the word "Enterprise" in script. Surrounding this word, and nearest to it, is a bead, consisting of a round dot and an oblong dot alternating. Around this bead is a plain ring raised. And around all of these is a wreath, oblong in form, and consisting of raised curves and lines in various shapes, as shown in the photograph.

The front door of the stove, located at the base, is bordered by a series of points alternating with each other in length, and all the points directed toward the centre of the door.

The corners of the base of the stove are provided with a leafed edged point.

On the section forming the top of the return-flues are the leafed edged points, the same as at the corners of the base, together with the long points on the door at the base, alternating each other.

The top of the stove is ornamented as follows:

The first, or base-ornament of the top, is composed of an acorn-shaped figure resting in or on a curve, which starts from each side of and below the base of the acorn, and after turning around and upward, terminates at or near the base of the acorn in two points, one pointing downward, and the other upward.

The second row of ornaments in the top is formed of two vertical sections of the cone, with two shoulders, one at about the middle of the side of the cone, and the other nearer the base. One of these vertical sections of the cone is smaller than the other, with the smaller one placed upon the larger one.

The third row of ornaments is the same as those on the section forming the top of the return-flues.

The fourth and top row of ornaments on the top of the stove is the same as that on the door in the base of the stove.

The ornamenting on the feed-door consists of four raised dots; then a leaf extending across the post-frame of the door, or so much of it or such a width of it as is covered by the raised dots; then four more dots, and then a leaf.

The dots and leaf are on the arch of the door, and in the centre of the upper part of the door, and within the two arms forming the central post, is a small five-leaved flower.

All the ornamenting herein described is raised work.

Having thus described my design,

What I claim, and desire to secure by Letters Patent, is—

The design for a stove herein set forth.

ALEXANDER WHITE.
